(57) **CLAIM**

The ornamental design for an air pump for inflating cushion bed, as shown and described.

DESCRIPTION

FIG. 1 is a top perspective view of an air pump for inflating cushion bed showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is another top view of the air pump for inflating cushion bed, showing two hooks folded away; and,

FIG. 9 is a rear perspective view thereof.

In the drawings, the broken lines shown in the figures depict environmental subject matter only and form no part of the claimed design.
